UNITED STATES PATENT OFFICE

2,459,194

SUCTION CLEANER DUST CHAMBER HAVING
A MOBILE WALL THEREFORCharles H. Sparklin, Chicago, Ill., assignor to
Birtman Electric Company, a corporation of
Illinois

Application November 30, 1944, Serial No. 565,871

2 Claims. (Cl. 15—352)

1

This invention relates to an improved suction cleaner combining the most desirable features of both the tank type cleaner and the floor type cleaner, and relates particularly to such an improved cleaner wherein there is provided an easily accessible dust collection chamber.

The improved suction cleaner set out herein is compact and light in weight. It uses a readily replaceable dust screen to collect the dust and a chamber adjacent the screen for holding the dust. The suction producing portion and the nozzle portion of the cleaner are adjacent each other with the nozzle portion hingedly attached to the suction producing portion. Thus the cleaner has the compact structure of the tank type cleaner yet avoids the long hose and wand of the ordinary tank type cleaner. It can be pushed around the floor like the ordinary bag type cleaner. A very important advantage is the provision of a side wall in the dust chamber through which dust can be removed. This wall is normally locked in closed air-tight position between the vacuum creating portion and the nozzle portion of the cleaner when the nozzle is arranged horizontally for cleaning but hangs free in vertical position when the nozzle portion is turned about its hinge; thereby permitting the collected dust to fall from the chamber.

This invention will be described in detail as set out in the embodiment shown in the accompanying drawings, of which: Figure 1 is a plan view of a vacuum cleaner; Fig. 2 is a vertical section taken along the line 2—2 of Fig. 1; Fig. 3 is a side elevation of the cleaner with the nozzle portion shown, by means of dotted lines, in raised position; and Fig. 4 is a front elevation of the cleaner.

The vacuum cleaner shown in the drawings includes a handle 10 attached to a vacuum producing portion 11 which is in turn attached, by means of hinges 12, to the nozzle portion 13 of the cleaner. There are provided wheels 14 on the bottom of the cleaner for pushing it along the floor. The usual motor (not shown) and fan 23 in the vacuum producing portion 11 of the cleaner are employed to cause air flow through the cleaner.

In the vacuum cleaner there is provided a yoke 15 at the rear of the cleaner for attaching the handle 10. The nozzle portion 13, which is attached to the vacuum producing portion 11 by means of hinges 12 and normally fits tightly against the vacuum portion, includes a front opening 16 adapted to rest on the rug or other article to be cleaned. This opening leads to a dust chamber 17 immediately above which is lo-

2

cated a removable dust screen 18 for entrapping dust from the air stream. The rear wall 19 of the dust chamber 17 is mounted on the rest of the nozzle structure by means of hinges 20 and is normally held between the vacuum producing and nozzle portions of the cleaner by means of a raised ridge 21 in the bottom of the dust chamber 17. When the two portions of the cleaner are locked together, the hinged wall 19 is held in air-tight contact between these portions. The locking means may be of any type desired and, as shown, comprises a small hook 30 on each side of the nozzle portion 13 adjacent the bottom thereof and engaging a pin 31 on the vacuum producing portion 11.

When the vacuum cleaner is in operation air is drawn through the front opening 16, as shown by the arrows of Fig. 2, through the removable screen 18 and through the air passage 22 above 20 the screen. While the air is going through the screen dust carried by this air is trapped on the screen and falls to the chamber 17 below. As soon as sufficient dust has been gathered in the chamber the nozzle portion 13 is turned to raised 25 position about its hinges 12, as shown by dotted lines in Fig. 3. This releases the hinged rear wall 19 of the dust chamber which hangs freely in vertical position and permits the dust to fall out of the chamber into a waiting receptacle. 30 When the dust has been thusly emptied the cleaner portions are once more locked together and the cleaner is again ready for operation.

Having described my invention in considerable detail as exemplified by one embodiment of the same, it is my intention that the invention be not limited by these details, unless otherwise specified, but rather be construed broadly within its spirit and scope as set out in the claims.

I claim:

- 40 1. A suction cleaner comprising a vacuum creating portion, a nozzle portion arranged forwardly of the vacuum creating portion and hingedly attached thereto at a point on the upper part of the nozzle portion, and an air passageway between the vacuum creating portion and the nozzle portion, said nozzle portion comprising a housing, a dust screen within said housing and across said passageway, a dust chamber forming a part of said nozzle portion and located adjacent said screen, a wall hinged at its top to the nozzle portion and extending between the screen and the bottom of the dust chamber and forming a side of said chamber through which dust can be removed from said chamber, and readily-releasable locking means for normally locking said wall

in airtight closed position between the vacuum creating portion and the dust collecting chamber, said nozzle and vacuum creating portions being turnable about their connecting hinge to permit pivoting of the nozzle portion upwardly to remove dust from the dust chamber.

2. In a suction cleaner a normally substantially horizontal nozzle portion, a vacuum creating portion, said nozzle portion being hingedly attached at its upper rear edge to said vacuum creating portion, an air passageway extending between the nozzle portion and the vacuum creating portion, said nozzle portion including a dust screen positioned across the air passageway, a chamber beneath said screen forming a part of said nozzle portion for collecting dust falling by gravity from said screen, and a substantially vertical wall hinged at its top to the nozzle portion and forming a part of said chamber extending from the screen to the bottom of the chamber and normally clamped between the two portions of the cleaner to form an air-tight seal, said nozzle and vacuum

creating portions being turnable about their connecting hinge to permit pivoting of the nozzle portion upwardly to remove dust from the dust chamber.

CHARLES H. SPARKLIN.
